UNITED STATES PATENT OFFICE.

WILLIAM SCHUMACHER, OF BROOKLYN, NEW YORK.

DESIGN FOR A SIGN-LETTER.

SPECIFICATION forming part of Design No. 21,147, dated November 3, 1891.

Application filed March 30, 1891. Serial No. 387,026. Term of patent 7 years.

To all whom it may concern:

Be it known that I, WILLIAM SCHUMACHER, a citizen of the United States, and a resident of the city of Brooklyn, in the county of Kings and State of New York, have invented and produced a new and original Design for Sign-Letters, of which the following is a specification.

Reference is to be had to the accompanying drawing, forming a part of this specification, in which the figure is a plan view of a portion of a sign showing my new design for sign-letters.

A represents a sheet of card-board, and B a

sign-letter sunken into the front surface of the card-board. The surface of the letter exhibits a series of circular sockets *a*, and these sockets exhibit a series of facets *c c*. The letter is surrounded by a dull surface of the card-board and a mottled surface *b* in outline of the letter.

What I claim is—

The design for a sign-letter herein shown and described.

WILLIAM SCHUMACHER.
